DESIGN FOR A CLOCK

Darryl Klay, Newark, N. J., assignor of one-third
to John G. Broady, New York, N. Y.

Application November 20, 1945, Serial No. 123,937

Term of patent 14 years

(Cl. D42—7)

To all whom it may concern:

Be it known that I, Darryl Klay, a citizen of the United States of America, residing in the city of Newark, in the county of Essex and State of New Jersey, have invented a new, original, and ornamental Design for a Clock, of which the following is a specification, reference being had to the accompanying drawing, forming part thereof.

In the drawing:
Fig. 1 is a plan view of a clock showing my new design; and

Fig. 2 is a perspective view thereof.

I claim:

The ornamental design for a clock, as shown.
DARRYL KLAY.
